UNITED STATES PATENT OFFICE.

JOHN S. MACKENZIE, OF DELAWARE, OHIO.

EGG-TURNING TRAY.

Application filed November 27, 1925. Serial No. 71,581.

The present invention is directed to improvements in egg turning trays for incubators.

The primary object of the invention is to provide a device of this character so constructed that the eggs can be periodically turned in an extremely simple and efficient manner.

A further object of the invention is to provide a device of this kind provided with a novel form of turning bar which can be operated to turn the eggs by hand or upon movement of the tray upon a table or other suitable support.

With these and other objects in view, this invention resides in the novel features of construction, formation, combination and arrangement of parts to be hereinafter more fully described, claimed and illustrated in the accompanying drawing, in which:—

Figure 1 is a top plan view.

Figure 2 is an enlarged sectional view on line 2—2 of Figure 1.

Figure 3 is an enlarged fragmentary longitudinal sectional view.

The tray consists of side and end bars, 1 and 2, respectively, of suitable wood, there being longitudinal slats 3 having their ends secured to the end bars. A wire mesh screen is supported by these slats and constitutes a bottom 4 for the tray and upon which the eggs are supported in transverse rows.

Secured to the inner face of each side 1 is a metallic plate 6 which extends the entire length of the side. The upper edge of this plate terminates in a downwardly bent portion 7 to provide a longitudinal guide groove 8, while the lower edge of said plate terminates in a flange 9 which rests upon the adjacent slat 3. The flange terminates in an outwardly bent portion 10 to produce a guide groove 11. In this manner upper and lower guide grooves are provided for both sides of the tray, the purpose of which will appear later.

In order to turn the rows of eggs successively a turning member 12 is employed and consists of a metallic bar 13 which is curved transversely, the convex surface of which has secured thereto by the crimped flanges 14 a sheet of sand-paper or other suitable material 15, the roughened properties of which producing friction to positively turn the eggs as the bar is slid under the rows thereof. To slidably connect the

bar with the flanges 9 the ends thereof terminate in hooks 16 for engaging the grooves 11. Secured to the ends of the bar 13 are the webs 17 of the angle member 18, the webs 19 thereof having pressed therein ribs 20 for slidably engaging the grooves 8, said ribs terminating in vertically disposed handles 21, which extend above the planes of the sides 1 in order that they may be conveniently grasped to slide the bar longitudinally.

Mounted upon the end bars 2 in any suitable manner are horizontally disposed plates 22 which are spaced from the screen bottom 4 to provide zones 23, into which the bar 13 enters after completing its travel from either end of the tray. It will be observed that the endmost rows of eggs will abut the plates 22, and since the bar can enter either of the zones, turning of the endmost rows are assured.

In Figure 1 of the drawing I have shown the tray used in connection with a table or other support 24 and upon which the tray may be placed for cooling and turning the eggs thereon at intervals. This table has sides 25 provided with stops 26 so that the handles 21 will engage therewith when the tray is slid inwardly and at which time the bar 13 will remain stationary and move under each row of eggs to turn the same during such sliding movement of the tray. It will be of course understood that the handles may be grasped and the bar slid to turn the eggs, it being apparent that as the bar is moved it will travel under the eggs with the sand-paper sheet 15 in a position to engage the eggs, thus simultaneously turning all eggs of each row and the rows successively.

What is claimed is:—

1. An egg turning tray for incubators comprising a frame, said frame having guide grooves associated with its sides, and an egg turning bar having hooks upon its ends slidably engaged with the grooves.

2. An egg turning tray for incubators comprising a frame, plates secured to the side bars of the frame and having upper and lower guide grooves carried thereby, angle members having ribs for slidably engaging the upper guide grooves, an egg turning bar having its ends secured to the angle members, hooks upon the ends of the bar for slidably engaging the lower grooves.

3. An egg turning tray having plates support, as and for the purpose set forth.

4. An egg turning tray having plates support, as and for the purpose set forth.

5. As a new article of manufacture, an egg turning bar curved transversely and having flanges upon its longitudinal edges, 15 a sheet of material having friction properties engaged upon the convex side of the bar, and retained thereon by said flanges.

6. In testimony whereof I affix my signature.

JOHN S. MACKENZIE.
